US0D1007428S

(12) **United States Design Patent** (10) **Patent No.:** **US D1,007,428 S**
(45) **Date of Patent:** **** Dec. 12, 2023**

(54) **CONNECTOR**

(71) Applicant: **Rosenberger Hochfrequenztechnik GmbH & Co. KG**, Fridolfing (DE)

(72) Inventor: **Markus Schichl**, Seekirchen (AT)

(73) Assignee: **ROSENBERGER HOCHFREQUENZTECHNIK GMBH & CO. KG**, Fridolfing (DE)

(**) Term: **15 Years**

(21) Appl. No.: **29/839,752**

(22) Filed: **May 24, 2022**

Related U.S. Application Data

(62) Division of application No. 35/510,949, filed on Nov. 10, 2020 (U.S. filing date under 35 U.S.C. 384), and having an international filing date of Nov. 10, 2020, now Pat. No. Des. 973,592.
